UNITED STATES PATENT OFFICE.

HENRY C. HARRISON, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-RECEIVER.

1,396,747.

Specification of Letters Patent.

Patented Nov. 15, 1921.

Application filed September 10, 1918. Serial No. 253,356.

To all whom it may concern:

Be it known that I, HENRY C. HARRISON, a citizen of the United States, residing at New York, in the county of New York, State of New York, have invented certain new and useful Improvements in Telephone-receivers, of which the following is a full, clear, concise, and exact description.

This invention relates to telephone receivers for general use in telephone or signaling circuits and has for its object to provide a receiver with an improved magnetic structure and one having its parts so proportioned and arranged as to provide an instrument of high sensitivity in responding to feeble alternating currents such as those generated by the voice waves impinging on a transmitter diaphragm. More specifically the object of the invention is to provide a telephone receiver having a balanced magnetic circuit arranged in such a manner as to operate efficiently and without causing undue distortion of the voice current wave forms. To attain this object the invention 25 consists of certain new and novel features of construction as will be more fully described and particularly pointed out in the appended claims.

In the accompanying drawings, Figure 1 is a view partly in section of a watch case type of receiver embodying this invention; Fig. 2 is an enlarged view in perspective of the magnetic structure of the receiver shown in Fig. 1, a portion of the upper pole piece 35 and the magnetic diaphragm being cut away to more clearly show the details of construction; Fig. 3 is a diagrammatic view of the magnetic circuit of the receiver shown in Fig. 1; Fig. 4 is a view partly in section of a slightly different form of receiver embodying this invention; Fig. 5 is an enlarged view of the magnetic structure and Fig. 6 is a diagrammatic view of the magnetic circuit of the receiver shown in Fig. 4; Fig. 7 is a view partly in section of another modification employing a permanent magnet; Fig. 8 is a sectional view of the receiver shown in Fig. 7 taken along the line 8—8 and looking in the direction of the small arrows; 50 and Fig. 9 is a diagrammatic view showing the magnetic circuit of the receiver shown in Fig. 7.

Referring first to Figs. 1 to 3, there is

shown a receiver casing 10 of the customary watch case type, preferably made of hard 55 rubber, and provided with a cap-piece 11 which is provided with screw threads adapted to engage similar threads on the casing member. The magnetic structure mounted within this casing comprises a lower member 60 12 which is secured to the base of the casing and an upper member 13 which is maintained in a certain position with respect to 12 by means of the threaded studs 14—14 and the lock nuts 15—15. The upper member 13 is provided with three pole pieces 16, 17 and 18. The middle pole piece 17 is equipped with a polarizing coil 19 and a talking coil 20 for the AC or talking currents. The lower member likewise is provided with three pole pieces 21, 22 and 23. Upon the middle pole piece 22 there is likewise provided a polarizing coil 24 and a talking coil 25 for the AC or talking currents. Located equidistant between the upper and the lower pole pieces is the magnetic diaphragm 26 which is provided with extension portions 27—27 whereby it is held in a fixed position which may be easily adjusted by means of the lock nuts 28—28 80 threading on the studs 14—14. Secured to the center of this diaphragm is the rod 29 which is also secured to the center of the main receiver diaphragm 30. The polarizing coils are connected in series and are so wound that with the current flow in the direction indicated by the arrows the middle pole of the upper magnet is made a south pole and the two outer poles are made north poles, while on the lower member the middle 90 pole is a north pole and the outer poles are south poles. The pole pieces positioned opposite each other are in each case of opposing polarity. The talking windings 20 and 25 are likewise connected in series and in 95 such a manner that current flowing through the windings in a given direction will make the two middle poles of one polarity while the outside poles will all be of the opposite polarity. This is represented in Fig. 3 by marking the outer pole pieces “+” and the middle pole pieces “—”, as showing the direction of flux at a given instant resulting from voice current flowing in the direction indicated by the small arrows. With current flowing through the talking windings 100 105

in the direction as designated, the operation of the receiver will be understood by an examination of the magnetic circuits. There are two paths for the steady or polarizing flux, one extending from outer pole piece 16 across the gap to pole piece 21, middle pole piece 22, across the gap to middle pole piece 17, and back to north pole 16, and the other from outer pole piece 18, across the gap to outer pole piece 23, to middle pole piece 22 across the gap to middle pole piece 17 and thence back to outer pole piece 18. The paths for the flux generated by current flowing in the talking windings with the direction of current as indicated are as follows:

- 5 1. From outer pole piece 16 across the gap to the diaphragm 26, thence across the gap to the middle pole piece 17 and back to outer pole piece 16.
- 10 2. From outer pole piece 21 across the gap to the diaphragm 26, thence across the gap to pole piece 22, and back to outer pole piece 21.
- 15 3. From pole piece 18 across the gap to diaphragm 26, thence across the gap to pole piece 17, and back to pole piece 18.
- 20 4. From outer pole piece 23, across the gap to diaphragm 26, thence across the gap to pole piece 22, and back to pole piece 23.
- 25 30 With the above paths for the polarizing or constant flux and the alternating flux at a given instant it will be noted that the flux from the talking winding is in a direction to augment the constant flux from poles 16 and 18 to the diaphragm, and from the diaphragm to pole piece 17 and in a direction to oppose the constant flux flowing from pole pieces 21 and 23 to the diaphragm and from the diaphragm to pole piece 22.
- 35 40 It will be thus seen that the effective flux flowing between the upper pole pieces and the diaphragm is increased, whereas the flux flowing between the lower pole pieces and the magnetic diaphragm is diminished and the magnetic diaphragm is accordingly drawn toward the upper pole pieces. With the current flowing through the talking windings in the opposite direction, the flux paths are such as to cause the diaphragm 50 to be drawn toward the lower pole pieces. Since the magnetic diaphragm 26 is rigidly secured to the main diaphragm 30 the latter follows the former in its excursions. With no current flowing through the polarizing windings 19 and 24, and with an ideal adjustment the effects of current flowing through the talking windings 20 and 25 neutralize each other and hence there is no tendency for distortion of the voice currents.
- 55 60 Referring now to Figs. 4, 5 and 6, there is shown a mechanical construction similar to the one described above yet having a somewhat modified magnetic circuit. In this case the receiver is also polarized by

magnetizing windings, the windings 31, 32, 33 and 34 being located on the outer pole pieces and arranged to provide the same polarization as the structure just described. The talking windings 35, 36, 37 and 38 are 70 also wound on the outer pole pieces and are connected together in such a manner that the polarity of the outer pole pieces of each member are of opposite polarity at any given instant and each is of the same polarity as the opposing outer pole piece, that is, at the instant pole piece 39 is made a north pole, pole piece 40 is made a south pole, pole piece 41 is made a south pole and pole piece 42 a north pole. The effect of current flowing through the talking windings is such as to make the middle poles neutral. The paths for the constant flux are the same as with the construction shown in Fig. 3. The paths for the alternating or talking flux 80 under the conditions indicated will be as follows:

1. From outer pole 39, across the gap to diaphragm 45, through the diaphragm and across the gap to pole 42, and thence back to pole 39 through the upper member 46.
2. From the outer pole piece 40, across the gap to diaphragm 45, through the diaphragm and across the gap to outer pole 41, and thence back to pole 40 through lower 95 member 47.

It will thus be seen that the alternating flux will be in a direction to augment the constant flow of polarizing flux across the gaps from pole piece 39 to the diaphragm 100 and from the diaphragm to pole 41, while the direction of the alternating flux across the gaps from pole 40 to the diaphragm and from the diaphragm to the pole 42, is such as to oppose the constant or polarizing 105 flux. The diaphragm will therefore be rotated in a clockwise direction, one end approaching pole 39 and the other end approaching pole 41. With current flowing 110 in the opposite direction through the talking winding, the direction of flux will be such as to cause the diaphragm to be rotated in the opposite or counter-clockwise direction. The magnetic diaphragm 45 is equipped with pivot extensions 48-48 which 115 engage suitable pivot holes in the blocks 49-49. These blocks are adjustable, being secured in place by the nuts 50-50, and the nuts in turn are threaded on the studs 51-51. The upper and lower members 46 and 47, respectively, are also secured in place by the nuts 52-52 threading on the studs 51-51. One end of the diaphragm is provided with an extension 53 to which is rigidly secured a stem 54 and the other end of this 120 stem is secured to a lever 55 which is pivoted at the bracket 56. The other end of this lever is also provided with a stem 57 which is rigidly secured to the main diaphragm 58. Thus vibrations set up in the magnetic 125

diaphragm 45 are repeated in the main diaphragm 58. Under certain conditions it might be found desirable to dispense with the lever member 55, in which case the stem 5 54 would be connected directly to the main diaphragm 58 in the manner shown in Fig. 1, the magnetic structure in this event being necessarily mounted at one side of the receiver casing.

10 In the modification shown in Figs. 7, 8 and 9, a semi-circular permanent magnet 60 is provided with a pair of polar extensions 61-62 disposed at either end of the permanent magnet and extending in opposite directions, these extensions being secured to the magnet by means of the screws 63-63. Secured to the upper member 61 is the soft iron cup 64 in which is mounted the coil 65 having a soft iron core 66. A similar 20 cup-shaped member 67 is secured to the lower member 62 and is provided with a coil 68 wound about the core 69. The cups 64 and 67 are separated from each other by means of a pair of shouldered non-magnetic 25 rings 70-71, between which is clamped the magnetic diaphragm 72. A stem 73 is connected at one end to the magnetic diaphragm 72 and at its other end to the main diaphragm 74, this stem projecting through 30 suitable openings in the core 66, cup 64, and pole extension 61. Thus any vibrations of the magnetic diaphragm are reproduced in the main diaphragm. The coils 65 and 68 are connected together in such a manner as 35 to make the middle poles of the same polarity as a result of any current traversing the windings. The paths for the constant or polarizing flux will in each case be directly across the gap from one cup member 40 and its core to the other member and its core. The paths for the flux set up by the alternating currents will be as follows:

1. From core 66, across the gap to diaphragm 72, thence extending radially 45 through the diaphragm and across the air-gap to cup-member 64, and back to core 66.
2. From core 69, across the gap to diaphragm 72, radially through the diaphragm and across the air-gap to cup-member 67, 50 and back to core 69.

Under this condition the flux generated by the voice currents is in a direction to augment the constant flux passing across the air-gap from the pole 66 to the diaphragm and to oppose the constant flux passing from the diaphragm to pole 69. The direction of flux between the diaphragm and the upper and lower cup members is such as to neutralize each other and moreover, the diaphragm at its outer edge is rigidly clamped against movement by the non-magnetic rings 70, 71. The center of the diaphragm is therefore drawn toward pole 66. In the same manner with current 65 flowing through the windings in the oppo-

site direction the center of the diaphragm would be drawn toward pole 69. Instead of employing the cup-shaped members 64 and 67 tri-polar extensions may be employed of the same type as shown in Figs. 2 and 5. 70

In all of the structures disclosed only the alternating current flux passes through the diaphragm longitudinally or in the plane of the diaphragm, since the manner in which the windings are placed on the cores is such 75 that any tendency for the polarizing flux to pass through the diaphragm longitudinally and to form separate magnetic circuits on either side of the diaphragm, would result in equal and opposing magneto motive 80 forces in the diaphragm. The polarizing flux, therefore, only passes through the diaphragm transversely, as pointed out above in explaining the flux paths for the different structures. Consequently the diaphragm 85 does not become saturated and bring about a loss in efficiency as would be the case if the polarizing flux were allowed to pass through the diaphragm longitudinally or in the plane of the diaphragm. Also in each of the 90 structures disclosed, there is provided a low reluctance path for the alternating current flux. The magnetic circuits moreover, are balanced in such a manner as to prevent any 95 distortion of the magnetic diaphragms and the resulting undesirable quality of transmission. While these magnetic circuits have been disclosed in connection with the receivers of the ordinary watch case type, their advantages are such that they might 100 very well be employed for other somewhat similar uses, such for example as sensitive alternating current relays or signaling devices and loud speaking receivers.

What is claimed is:

1. In a telephone receiver, a magnetic diaphragm, a set of three pole pieces oppositely disposed on either side of the diaphragm, means for giving opposing pole pieces constant opposite polarities, and additional 110 means for giving opposing pole pieces variable like polarities.

2. In a telephone receiver, a magnetic diaphragm, a set of three pole pieces disposed on one side of the diaphragm and opposed by a corresponding set of three pole pieces on the other side of the diaphragm, means for giving opposing pole pieces constant opposite polarities, and additional means for superimposing variable polarities of like 120 sign upon opposing pole pieces.

3. In a telephone receiver, a magnetic diaphragm, a set of three pole pieces disposed on each side of the diaphragm and in opposite relation to each other, a magnetizing 125 winding for each set of pole pieces, said magnetizing windings being so connected as to establish constant flux paths between the opposing pole pieces on either side of the diaphragm, and additional windings for the 130

1
pole pieces so connected as to establish variable flux paths between the different pole pieces on the same side of the diaphragm.

4. In a telephone receiver, a magnetic diaphragm, an odd number of pole pieces disposed on each side of the diaphragm and separated therefrom by air-gaps, means for establishing constant flux paths across said air-gaps between opposing pole pieces, and 10 additional means for establishing variable flux paths between the pole pieces on each side of the diaphragm.

5. In a telephone receiver, a magnetic diaphragm, a set of three pole pieces oppositely disposed on either side of the diaphragm, means for constantly maintaining oppositely positioned pole pieces at opposite magnetic polarities, and additional means for superimposing on said pole pieces periodically 20 variable magneto motive forces producing at any instant like polarities on said oppositely positioned pole pieces.

6. In a telephone receiver, a magnetic diaphragm, means for producing a constant 25 magneto motive force, means for producing a periodically varying magneto motive force, magnetic structures on opposite sides of the

magnetic diaphragm, said magnetic structures and said diaphragm jointly affording a plurality of magnetic circuits for the flux 30 produced by said constant magneto motive force and each of said magnetic structures and the diaphragm affording a plurality of independent magnetic circuits for the flux produced by said varying magneto motive 35 forces.

7. In a telephone receiver, a casing, a cap portion therefor, a diaphragm clamped between said casing and cap, and a magnetic structure inclosed within said casing, said 40 magnetic structure comprising a magnetic diaphragm rigidly connected to said first diaphragm, an odd number of magnetic pole pieces disposed on either side of said magnetic diaphragm and in opposite relation to 45 each other, means for oppositely magnetizing opposing pole pieces, and additional means for magnetizing opposing pole pieces to the same polarity.

In witness whereof, I hereunto subscribe 50 my name this 29th day of August A. D., 1918.

HENRY C. HARRISON.
